CLAIM

The ornamental design for an aerodynamic transporter, as shown and described.

DESCRIPTION

FIG. 1 is a perspective view of the transporter-as viewed from the left, front side of the transporter;

FIG. 2 is a left side elevation view of the transporter;

FIG. 3 is a right side elevation view of the transporter;

FIG. 4 is a top view of the transporter;

FIG. 5 is a rear view of the transporter; and,

FIG. 6 is a front view of the transporter.

The portions of the aerodynamic transporter shown in broken lines form no part of the claimed design.
